UNITED STATES PATENT OFFICE.

BÉLA GÉZA MÉSZÁROS, OF HAMBURG, GERMANY, ASSIGNOR TO HIMSELF, IVAN KAHN, AND ADOLF LEOPOLD PAUL MERTENS, OF HAMBURG, GERMANY.

SPITTOON.

SPECIFICATION forming part of Letters Patent No. 740,891, dated October 6, 1903.

Application filed March 23, 1903. Serial No. 149,186. (No model.)

To all whom it may concern:

Be it known that I, BÉLA GÉZA MÉSZÁROS, a subject of the Emperor of Austria-Hungary, residing at Hamburg, Germany, have invented 5 certain new and useful Improvements in Spittoons, of which the following is a specification.

This invention relates to a spittoon apparatus in which the bowl or cup of the spittoon is excluded from the outer atmosphere 10 by powerfully-acting means of closure, but is accessible when necessary by pulling down or drawing out the holder or casing containing the said bowl or cup. The spittoons heretofore employed in living-rooms, restaurants, 15 public buildings, hospitals, &c., have not fully conformed to sanitary requirements. The filling of spittoons with water or sand heretofore employed does not prevent the spreading of contagious diseases, seeing that, as has 20 been scientifically proven, the employment of water does not prevent the transmission of matter containing hurtful bacilli by insects, &c., and that by the employment of sand disease-bearing matter arises in the shape of 25 dust, which acts contagiously by being carried about in the atmosphere. These objections are completely obviated in the present invention by the use of an air-tight cover for the spittoon and the employment for the spittoon itself of easily-changed bowls or cups impregnated with disinfecting fluid and placed 30 one over the other to any number in what may be called a "bowl-holder" and each of which is removable as and when convenient. The 35 aforesaid arrangement allows of the spittoon apparatus being applied to the ceilings and walls of rooms in which heretofore the question of space has rendered the employment of spittoons almost or quite impossible, especially 40 in railway or tramway carriages, ships, &c. Spittoon apparatus arranged in accordance with this invention is especially suited for use in hospitals, as in this case ready accessibility of the bowl and the air-tight shutting in of the contagious-disease germs are of 45 the highest importance.

The accompanying sheet of drawings shows a spittoon apparatus constructed in accordance with the invention as applied to the 50 ceiling of a railway-carriage compartment, for example.

Figure 1 represents a sectional elevation of the complete apparatus; Fig. 2, a side view showing the bowl-holder *c* drawn down a short distance from the upper part *a*, and Fig. 3 a 55 plan.

The apparatus consists, first, of a part *a*, fixed to the ceiling, and, secondly, of a holder *q* for the reception of the specially-constructed spittoons *s*. The part fixed to the ceiling 60 consists of a casing *a*, in the interior of which bearings *c*, closable by covers *b*, carry a shaft *d*. This shaft, with its connected parts, can easily be removed if and when required by first taking off the covers *b* and then lifting 65 the journals of the shaft out of the bearings *c* and passing them out through the spaces *e*. On the shaft *d* are fixed two cord-drums *f* and a bevel-wheel *g*, which gears with a second bevel-wheel *h*. The axis *k* of the latter takes 70 a bearing above in a circular opening in the cross-piece *i*, which is fixed in any suitable way to the inside of the casing *a*. The axis *k* of the bevel-wheel *h* engages at its lower end by a conical recess with the point of a 75 pin *l*, which, as well as the cylindrical spring-case *n*, is fixed to the bottom *m* of the casing *a*. The spring-case *n* is closed above with a cover *o*, fixed to the boss of the bevel-wheel *h*. One end of the spiral spring *p* is fixed to the 80 case *n* and the other to the axis *k*. The cords *z*, wound on the drums *f*, pass through openings in the bottom *m* of the casing *a* and are fixed in any suitable way to the inside of the bowl-holder. This latter consists of a casing *q*, 85 the inwardly-projecting bead *r* of which serves as a bearer for a number of spittoon-bowls *s*, made of paper or other suitable material impregnated with disinfecting fluid and placed one in and over the other. Above 90 the bowls is a funnel *t*, open at the bottom and arranged to turn on a hinge or to be otherwise removable from its seat when required. The ring *w*, screwed to the casing *q*, serves as a handle for drawing down the 95 bowl-holder. The upper edge of the casing *q* is pressed tightly against an india-rubber ring *u*, placed in a groove *v*, whereby an air-tight closing in of the spittoon-bowls in the bowl-holder *q* is effected. 100

It will now be understood that by pulling the ring *w* downward the bowl-holder *q* is

drawn away from the upper part *a*, exposing the funnel *t* to receive the expectoration, which it conducts into the uppermost bowl *s*. The drum *f* and thereby the bevel-wheels *g* and *h* are at the same time rotated, so that the axis *k* rotating therewith effects a winding up of the spiral spring *p*, connected to it. The energy thus stored up serves to effect the automatic upward return of the bowl-holder 10 to its normal position after use.

The emptying of this apparatus is effected as follows: The uppermost of the bowls *s* is removed by any suitable handle after raising of the funnel *f*. (See dotted line, Fig. 15 2.) As the bowls are made of very cheap material, they can be frequently changed and thrown away—for example, when employed in railway-carriages after each journey. Instead of fixing the apparatus to the ceiling it 20 may be fixed to the wall, in which case the spring or other power-storing gear may be so arranged that it is wound up or set by exerting a horizontal pull on the bowl-holder. The power for returning the bowl-holder to its 25 normal position and pressing it firmly against the ring *u* may be produced by any other suitable arrangement—as, for example, by the direct winding up of a spiral spring on the shaft *d* or by the counterweight, &c.

30 What I claim, and desire to secure by Letters Patent of the United States, is—

1. In a spittoon-supporting device, a plurality of spittoon-bowls adapted to be nested within a movable holder, means for automatically pressing said holder against a fixed casting, means whereby the pressure effects an air-tight inclosure of said spittoon-bowls, 35

means for pulling said bowl-holder downward whereby the spittoon-bowls are rendered accessible, means for returning said 40 bowl-holder to its normal closed position through energy stored up by the downward movement of same.

2. In a spittoon-supporting device, a bowl-holder, cords attached to said bowl-holder, a fixed support, a shaft mounted on said fixed support, drums on said shaft upon which said cords are wound, a spiral spring mounted on said fixed support, gearing connecting said shaft to said spring, whereby the energy 50 stored up in lowering the spittoon is employed to raise the same after use, said spring being arranged for continually exerting tension on said cords, whereby said bowl-holder is normally held pressed against said fixed support 55 and means upon said support whereby an air-tight contact is formed between said bowl-holder and said fixed support when the same are pressed together.

3. In a spittoon-supporting device, a bowl- 60 holder, means for adjustably suspending the same from a fixed support, and for holding the same pressed against said fixed support when in normal closed position, and means whereby an air-tight contact is formed between 65 said bowl-holder and said fixed support when they are pressed together.

In testimony whereof I have hereunto set my hand in the presence of two witnesses.

BÉLA GÉZA MÉSZÁROS.
